INVENTOR:

John Braun,
BY *John A. Giedersheim,*
ATTORNEY.

UNITED STATES PATENT OFFICE.

JOHN BRAUN, OF PHILADELPHIA, PENNSYLVANIA.

SHAFT-COUPING.

SPECIFICATION forming part of Letters Patent No. 292,978, dated February 5, 1884.

Application filed May 15, 1882. (No model.)

To all whom it may concern:

Be it known that I, JOHN BRAUN, a citizen of the United States, residing in the city and county of Philadelphia, State of Pennsylvania, have invented a new and useful Improvement 5 in Shaft-Couplings, which improvement is fully set forth in the following specification and accompanying drawings, in which—

Figure 1 is a side elevation of the shaft-coupling embodying my invention. Fig. 2 is a longitudinal section thereof in line xx , Fig. 3. Fig. 4 is a transverse section in line zz , Fig. 2. Fig. 5 is an end view thereof. Fig. 15 Fig. 6 is a view of the interior of the coupling. Similar letters of reference indicate corresponding parts in the several figures.

My invention consists of a shaft-coupling having a clamp which is operated by a screw, 20 the action whereof is to compress the clamp against the shaft in a powerful and secure manner.

It also consists of certain details of construction, as will be herein set forth.

25 Referring to the drawings, A represents the body of the coupling or hub of a pulley or wheel, and B B the shafts to be coupled, said body being hollow and provided at its ends with heads C C', whose centers have openings for the reception of the shafts. The head C is formed separate from the body and attached thereto by means of screws D, which are passed through openings in said head, and engage with lugs E, which are cast with the body A and project from the inner face thereof. The other head, C', is cast with the body, but may be made and attached similar to the head C.

30 F represents a clamp, which is somewhat of U shape, and located within the body A, said clamp having an opening near its bend or crown for the reception of the ends of the shafts B B, the limbs F' of the clamp constituting jaws, being separated, and having recesses on their outer faces, in which are fitted nuts G G, of which in the present case there are two on each side. In the jaws F' are transverse openings coincident with the openings of the nuts G, for the passage of screws H, 45 which engage with said nuts.

Projecting longitudinally from the ends of the clamp F are teats or studs J, and in the heads C C' are openings a, which are adapted to receive said studs J, whereby the clamp is connected with the body and the two move as 55 one.

In the wall of the body A are openings K, which occupy coincident positions with the heads of the screws H, so that said screws may be rotated from without the body A by means 60 of a key, wrench, or other suitable implement inserted through said openings K.

In the heads C C' are openings L, which register with the space between the limbs or jaws F' of the clamp F, whereby a wedge may 65 be introduced into said space through the openings L, for forcing apart said jaws should they stick on the shaft after the screws H are loosened. The screws H are of the order of differential, the pitch of the threads of the nuts G 70 G on opposite sides of the jaws F' being different to accommodate the difference of the threads of the screws.

It will be seen that when lengths of a shaft are inserted in the clamp and the screws H 75 rotated in the proper direction the jaws F' are brought together, whereby the clamp is tightened against the said lengths of the shaft in a powerful and secure manner, so that said lengths of the shaft are reliably coupled without liability to slip or disengage. When the screws are rotated in opposite direction or loosened, the jaws are relieved, whereby the two lengths of the shaft are adapted to be removed from the coupling and reapplied or replaced. When an ordinary screw is employed in lieu of the differential screw H, the former is journaled to one of the nuts G and engages with the opposite nut, so that the legs F' F' of the clamp, which expand and contract, may 90 be brought together or permitted to separate for the purpose of holding or releasing the lengths of the shaft. The body or shell A protectively incloses the clamp and adjacent parts, and when made of cylindrical form may 95 be employed as a pulley, as is evident.

I do not claim, broadly, a shaft-coupling having an internal clamp provided with a differential screw and nuts.

Having thus described my invention, what I 100

claim as new, and desire to secure by Letters Patent, is—

1. A coupling having an internal clamp and a screw fitted thereto, and an exterior shell formed with an opening, whereby said screw is accessible and movable from the outside of the shell, substantially as and for the purpose set forth.

2. In a coupling, an internal clamp having a differential screw and nuts, in combination with an exterior shell, which, connected with said clamp, is formed of one piece of metal, substantially as and for the purpose set forth.

3. In a coupling, an internal clamp having a differential screw and nuts, and exterior shell formed at its ends with heads, which are connected with said clamp, substantially as described.

4. In a coupling, an internal clamp having

studs J, in combination with the exterior body or shell, having openings a, which receive said studs, substantially as and for the purpose set forth.

5. A clamp having legs F', in combination with the heads of the exterior body or shell, having openings L coincident with the space between said legs, substantially as and for the purpose set forth.

6. In a coupling, a hollow body or shell, in combination with a clamp having means for attaching it with the heads of said body, one or both of said heads being removably connected with said body, substantially as and for the purpose set forth.

JOHN BRAUN.
